UNITED STATES PATENT OFFICE.

CHARLES HENRY AUGUSTUS FREDERICK LOCKHART ROSS, OF BALNAGOWAN CASTLE, COUNTY OF ROSS, SCOTLAND.

MAGAZINE-FIREARM.

No. 802,117.

Specification of Letters Patent

Patented Oct. 17, 1905.

Application filed December 5, 1901. Serial No. 84,742.

To all whom it may concern:

Be it known that I, CHARLES HENRY AUGUSTUS FREDERICK LOCKHART ROSS, baronet, a citizen of Great Britain, and a resident of 5 Balnagowan Castle, county of Ross, Scotland, have invented certain new and useful Improvements in Magazine-Firearms, of which the following is a specification.

This invention is an improved cartridge lifting or feeding device for magazine-firearms, the object being to provide a simple and effective device for supporting and elevating cartridges in the most advantageous manner for transferring them one by one from the 15 magazine to the firing-chamber of the firearm.

Figure 1 of the drawings is a side view in section, taken through the longitudinal center of the relevant features of a firearm and its magazine, showing the carrier in its lowest 20 position supporting a series of cartridges. Fig. 2 is a rear view in cross-section, taken on the line 2 2 of Fig. 1. Fig. 3 is a rear view in section, taken substantially along the line 3 3 of Fig. 1. Fig. 4 is a fragmentary view 25 of the right-hand side of the firearm, showing the projecting handpiece and an index arrangement in connection therewith. Fig. 5 is a side view of a fragmentary portion of a gun, showing a finger or thumb lever for operating the 30 cartridge-carrier. Fig. 6 is an end view in cross-section, taken on the line 6 6 of Fig. 5. Fig. 7 is a fragmentary side view showing the connection between the thumb-lever and the arm of the carrier.

The cartridge-carrier 5 is here shown to be 35 adapted for supporting a double file of cartridges *c* in zigzag relation, as is best shown in Fig. 3, the uppermost cartridge projecting into the path of movement of the bolt 6 when 40 the latter is drawn back, so that the bolt will carry that cartridge forward to the firing-chamber of the gun. The carrier is extended forward and is pivotally supported in any convenient way at 7, which is approximately at 45 the point or plane of convergence of the forwardly-projected center lines 9 of the cartridges *c* as they rest one upon the other in packet form in the magazine. The pivot-pin 7 may be supported at its ends in the stock of 50 the gun or it may be supported in a small bracket or block dovetailed or otherwise secured to the under side of the barrel.

A spring 8, of any approved construction, is preferably employed for elevating the car-

tridge-carrier with a yielding pressure, and 55 that spring may be applied at any convenient portion of the length of the elevator, according to the type of gun or the pressure and amplitude of movement required.

As a means for enabling my improved carrier to be operated or controlled by the operator at all times, I preferably provide the handpiece 10, (shown in Figs. 1, 2, and 4,) which is either attached to or integral with the carrier and which extends therefrom at a point 60 conveniently within the reach of the operator and preferably upon the right-hand side of the gun at that portion thereof which would most naturally be held or supported by the left hand of the operator during the firing and charging 65 operations, so that the operator may during either of these operations manipulate the carrier positively in both directions if necessary with one or more of the otherwise unoccupied fingers of his left hand. The projecting portion of the handpiece is preferably made with a downwardly-turned lip 11, which fits against the outer side of the stock, and may be made long enough to cover the slot through which 70 the handpiece projects at all positions thereof. 75

Some convenient projecting visible portion of the carrier may be utilized as a cartridge-index for indicating the number of cartridges contained in the magazine at any time. This may be accomplished, as shown in Fig. 4, by 80 a graduated plate 13 at the side in connection with the lower edge 14 of the lip 11, or the 85 graduations may be placed on the handpiece itself and the index-mark be on a stationary plate or on the stock. By practice also the 90 operator may become sufficiently expert to determine the number of cartridges in the magazine by the sense of touch alone, according to the position occupied by the handpiece.

In some cases or by some military authorities it may be considered desirable to operate the carrier by means of a thumb-lever, as shown in Figs. 5 and 6. This thumb-lever is 95 preferably an integral piece, comprising the thumb-lever 18, the shaft 19, and the toe 20, 100 mounted in the bracket 21, secured to the under side of the stock 22 of the gun. The toe 20 is located in engaging relation to a depending arm 23 of the elevating carrier 24. The thumb-lever stands in a convenient position 105 to be reached by the thumb or a finger of the operator's left hand and may be placed upon either side of the gun. This toe works the

carrier against the pressure of its spring, which may be employed as shown in Fig. 1.

In charging the magazines which employ my improved carrier the cartridges may be inserted either from a clip or directly by the hand of the operator, the pressure imparted through the cartridges carrying the carrier to its lowermost position, or the operator may by means of the handpiece 10 of Fig. 2 or by means of the thumb-lever 18 in Figs. 5 and 6 depress the carrier to its lowest position with one hand, while charging the magazine with the other hand. It is preferable thus to depress the carrier in most cases, since the cartridges will then readily fall to their proper position. If at any time either during the charging or firing operations the cartridges should become displaced or jammed in the magazine either from accident or inadvertence from the presence of dirt or from the use of defective ammunition, the jam may be instantly released by pressing the carrier downwardly away from the lowermost cartridge, thereby permitting it and the cartridges above it to drop down, and thus freeing them from their jammed relation without opening the gun or seriously interrupting the operation thereof or even changing the normal positions or movements of the operator, inasmuch as his left-hand most naturally supports the firearm, with the ends of his fingers in the immediate vicinity of the handpiece or the thumb-lever.

On account of the simplicity in form and function of this carrier (shown in Figs. 1 to 4, inclusive) it may be made in a single integral structure, and if for constructive reasons it may be found preferable to make it in two or three pieces these should be riveted or otherwise securely fastened together, so that the carrier is in form, operation, and effect a single integral piece. Although some form of spring is preferably employed for elevating the carrier, the operation of the latter is not dependent upon the spring. If the spring should be broken, the carrier may still be operated in both directions by the operator's hand without interrupting the operation of the firearm and without seriously impairing its efficiency.

The shape of the carrier and the manner of operating it may be modified in various ways to suit different types of firearms or to suit particular environments or conditions without departing from the essence of the invention.

The carrier being entirely inclosed within the walls or recess of the firearm is thereby protected against the entrance of dirt and is also protected from injury due to blows from the outside or due to the dropping of the firearm, the only entrance for dirt being through the top of the receiver, and then only when the bolt is drawn back, thereby reducing to a minimum the opportunities for the entrance of dirt or other foreign substances.

I claim as my invention—

1. The combination with a firearms-magazine, of a cartridge-carrier mounted for oscillation and entirely inclosed within the firearms structure, and having a handpiece extending through a slotted opening in the side of the firearms structure at a substantial distance from the pivot.

2. The combination with a firearms-magazine, of a cartridge-carrier mounted for oscillation and entirely inclosed within the firearm structure and having a handpiece extending through a slotted opening in the side of the firearm structure at a substantial distance from the pivot, and means appurtenant to the handpiece for closing the slotted opening at all positions of the handpiece.

3. The combination with a firearms-magazine, of a cartridge-carrier mounted for oscillation and entirely inclosed within the firearm structure, and a handpiece appurtenant to the carrier, extending through a slotted opening in the side of the firearms structure, at a substantial distance from the pivot of the carrier, the handpiece being provided with a lip extending in the direction of the extension of the slotted opening to cover that opening at all of the positions of the handpiece.

CHARLES HENRY AUGUSTUS

FREDERICK LOCKHART ROSS.
